UNITED STATES PATENT OFFICE.

PETER L. HUDSON, OF EFFINGHAM, ILLINOIS.

WEATHER-STOP.

1,213,103.

Specification of Letters Patent. Patented Jan. 16, 1913

Application filed July 6, 1916. Serial No. 107821

To all whom it may concern:

Be it known that I, PETER L. HUDSON, a citizen of the United States, residing at Effingham, in the county of Effingham and State of Illinois, have invented certain new and useful Improvements in Weather-Stops; and I do declare the following to be a full, clear, and exact description of the invention, such as will enable others skilled in the art to which it appertains to make and use the same.

My invention is an improved weather stop for application to outside doors of any kind of buildings, the invention, however, being primarily adapted for use in connection with the doors of dwellings.

The main object of the invention is to provide a vertically movable weather stop operatively connected with the rocking knob shaft of the door lock in such a manner as to be raised automatically when said shaft is rocked to release the door latch, and to provide means whereby the connections between the shaft and stop may be locked against movement, thus permitting the stop to be held in lowered position and at the same time locking the door closed.

With the foregoing general object in view, the invention resides in certain novel features of construction and in unique combinations of parts to be hereinafter fully described and claimed, the descriptive matter being supplemented by the accompanying drawings which constitute a part of this application and in which:

Figure 1 is a side elevation of a door showing the application of the invention thereof; Fig. 2 is an enlarged elevation with the weather stop locked in lowered position; Fig. 3 is a similar view with said stop secured in raised position; Fig. 4 is a vertical transverse section on the plane of the line 4—4 of Fig. 1; Fig. 5 is a horizontal section on the plane of the line 5—5 of Fig. 1; Fig. 6 is a detail transverse section on the line 6—6 of Fig. 3; Fig. 7 is a horizontal section as seen on the plane indicated by the line 7—7 of Fig. 6; and Fig. 8 is a perspective view of the locking member.

50 In specifically describing the structure shown in the drawings above briefly described, similar characters will be employed to designate corresponding parts throughout the several views and reference will be herein made to the numerous elements by their respective indices. To this end, the numeral
55

1 designates a door frame in which a door 2 is hingedly mounted, said frame having the usual door sill 3 at its lower end. The door 2 is provided with a suitable lock 4 whose latch is released in the usual manner by the rectangular rock shaft 5 which is equipped with knobs 6 on its ends, this shaft serving as the operating member for the invention as well as that of the latch in the manner to be described. 60 65

Contacting slidably with the inside of the door 2 at the lower end thereof is a vertically sliding weather stop 7 which may be either constructed of wood or metal, said stop being slidably connected to the door by screws 8 passing through slots 9 in plates 10 which are secured to the inner face of said stop, this face being recessed for the reception of the screw heads as shown clearly in Fig. 6. 75 The lower ends of the slots 9 are preferably enlarged as shown at 11 whereby when the stop 7 has been raised to its limit, the heads of the screws 8 may pass through said enlarged ends to permit removal of the entire 80 stop should this be desirable. This also facilitates attachment of the stop as will be readily understood.

A member 12 preferably in the form of an upright bar-like casting is provided with 85 ears or the like 13 which are riveted or otherwise secured to the stop 7, the portion of the member 12 in contact with said stop thus serving to reinforce the latter and to prevent warping thereof whether it be of 90 metal or wood. Perforated ears 14 are formed integrally with and extend toward the door from the upper portion of the casting 12 and receive therein the lower end of a rod 15 whose lower end has thereon a nut 95 16. The upper end of rod 15 is pivoted to one end of a bell crank 17 which is fulcrumed at 20 to the door, preferably upon the thickened central portion of the latter, while pivoted to the other end of said crank 100 is a horizontal operating bar 21 having therein a longitudinal slot 22 through which a screw or other suitable fastener 23 passes to slidably support said bar from the door.

A cross bar 24 is provided at its center 105 with a rectangular opening through which the rock shaft 5 passes, the ends of said head being connected by small chains or the like 25 with the adjacent end of bar 21. When the door is shut and latched, the cross bar 110 24 stands vertically and both chains 25 are taut, and the bar 21 is then so disposed as to

lower the weather stop 7 onto the door sill 3. When, however, either knob 6 is turned in one direction or the other, the bar 24 will be rocked and will pull upon one of the 5 chains 25. The result of this is that the bar 21 will be shifted and in so doing will rock the bell crank 17 to raise the rod 15, thus elevating the stop 7 clear of the sill to permit the door to open without binding. If 10 said door is to be held in opened position, the knob will be released with the result that the stop 7 will descend and in so doing a door checking shoe 26 which is mounted on the lower end of the casting 12, will be 15 brought into contact with the floor, thereby holding the door in its opened position.

The shoe 26 may be of any suitable construction, but it is preferably in the form of a rocker plate pivoted at 27 to the lower 20 end of casting 12, the pivot being disposed below the center around which the curved edge of the plate is described. This will cause the end portions of the shoe 26 to engage the floor forcibly if the door tends to 25 move in either direction and thus said door will be held against further movement.

Pivottally mounted upon the outer end of the screw 23 is a locking plate 28 which is substantially triangular, being pivoted at 30 one of its angles and having at this angle an arcuate operating arm 29 while at another of its angles or corners a stop 30 is provided, the edge between this angle and the remaining one being preferably curved 35 as shown for coöperation with a stop 31 which projects outwardly from the bar 21 adjacent one end of its slot 22 (see Fig. 2). When the plate 28 is swung to the position shown in this figure, the bar 21 cannot move 40 toward the shaft 5 and thus the chains 25 and cross bar 24 will prevent rotation of said shaft, thus locking the door closed. When swung to the position shown in Fig. 3, however, a pin 32 which projects laterally from the free end of the arm 29 will 45 abut a shoulder 33 at the upper edge of bar 21, when the latter is moved to its limit toward the shaft 5. Thus, it will be seen that the bar may be locked in either position to 50 support the weather stop 7 above the floor or to retain said stop in operative position as occasion may demand. Particular em-

phasis is laid upon the fact that the double acting member 28 while locking the bar 21 in one position also locks the door.

55

From the foregoing taken in connection with the accompanying drawing, the construction, manner of operation, and advantages of the invention will be readily understood and it will be appreciated that 60 within the scope of the appended claims, numerous changes may be made without sacrificing the main advantages thereof.

I claim:

1. A device of the class described comprising a horizontal weather stop and means for mounting it for vertical movement on the lower end of a door, a horizontally movable bar having a horizontal slot, a fastener passing through said slot for connecting the 70 bar slidably with the door above the weather stop, a locking member for said bar, the aforesaid fastener serving as a mounting for said member, and operating connections between said bar and the weather stop for 75 moving the latter vertically when said bar is moved horizontally.

2. A device of the class described comprising a horizontal weather stop and means for mounting it for vertical sliding on the 80 lower edge of a door, an operating bar for said stop, said bar having a longitudinally extending slot, a fastener passing through said slot for connecting the bar slidably with the door, a stop on said bar adjacent 85 one end of its slot, a double acting locking member pivottally mounted on said fastener and having a shoulder to abut said stop when said member is swung to one position to prevent movement of the operating bar 90 in one direction; other stops respectively on the bar and locking member for holding said bar against movement in the other direction when said locking member is swung to its reverse position, and operating connections between said bar and the stop.

In testimony whereof I have hereunto set my hand in the presence of two subscribing witnesses.

PETER L. HUDSON.
